Claims priority, application Sweden Nov. 25, 1959
7 Claims. (Cl. 102—34.4)

The present invention relates to rocket devices of the type used for signalling and other purposes. More particularly the invention relates to rocket devices comprising an outer container and a rocket casing adapted to be expelled from said container, and a useful load, such as light signal device, in said casing and connected by cords or lines with a foldable parachute.

An object of the invention is to provide the rocket device in such a manner that a relatively short length and small volume of this device is obtained.

Another object of the invention is to provide a rocket having excellent flight stability.

Still another object of the invention is to provide an improved connection between the useful load and the suspension cords connecting said load to the parachute.

Other objects of the invention are made clear by the following description with reference to the accompanying drawing showing as example a rocket device according to the invention. FIG. 1 is an axial section of the rocket device, and FIG. 2 is a side view of a shell for the useful load and the parachute device for suspension of said shell and load after these parts have been expelled from the rocket casing.

In the drawing, 1 indicates a tubular outer container, 2 indicates a cap closing the bottom end of said tubular container whereas 3 indicates a cap closing the top end of the same container. The container 1 as well as the caps 2 and 3 are cylindrical and have a circular cross-section. The end portions 4 and 5 respectively of the tubular container 1 have reduced cross-sections so that any level differences are not present in the joints 2' and 5' between the caps and the container. Owing to this fact, said joints may be effectively sealed by means of tapes sized to the parts. Said tapes are not shown in the drawing. The bottom or rear end of the container 1 is closed by a bottom plate 6 with an axial guide-socket 7 for a striking pin 8. The firing mechanism comprises a metal wire or spring 9 which by means of a screw 10 is fastened to the bottom plate 6 whereas the opposite free end of the wire or spring is inserted in a diametrical bore 11 in the lower end portion of the striking pin. By an angular rotation of the cap 2 the spring 9 is drawn out from engagement with the bore 11 after which the firing pin spring 12 is free to force said pin for initial firing of the percussion cap or primer 13. This cap or primer is inserted in a washer or ring 13' which together with the primer covers the outlet opening of a jet tube 14 for the combustion gases of the rocket fuel 18. The primer may be enclosed by a cover 15 of plastic or wax cloth sealing the opening of the jet tube and preventing removal of the primer 13 and washer 13' from the opening of said tube. From the narrow intermediate portion 14' the jet tube widens rearwardly with relatively small cone angle and has a fore portion 16 with a larger cone angle. The

2

latter portion 16 is connected to the rear end of a cylindrical or tubular motor housing 17 containing solid rocket fuel or powder 18. The motor housing 17 is partially inserted into and attached to the rear end portion of the cylindrical or tubular rocket casing 19 which above or in front of the motor housing 17 contains a tubular or cylindrical shell 20 disposed coaxially to the casing 19 and the tube 1 and enclosing the useful load consisting, for example, of an illuminating composition 21. Between this composition and the fuel body 18 for expelling and propelling the rocket a composition 18' is fitted, said composition forming a delay fuse in the releasing of the shell 20 with the illuminating composition 21 from the rocket casing 19.

In order to improve the flight properties of the rocket it may be provided with a guide fin device consisting, for example, of a plurality of blades 25 of steel projecting from a hub on the jet tube or nozzle 14. This hub is formed by two rings or washers 26 between which the inner ends of the blades 25 are clamped. These blades constitute a guiding and stabilizing factor especially in the start when such a factor is most required. After leaving the container 1 the resilient blades 25 will be straight and project radially from the hub 26 but as the speed of the rocket and the air resistance increases the blades by this resistance will be bent toward the position shown in FIG. 1.

The tubular shell 20 for the illuminating composition 21 has substantially smaller outer diameter than the inner diameter of the rocket casing 19 so that an annular space 22 will be provided between the parts 19 and 20. A supporting ring 23 is attached to the shell 20 and separated from the delay fuse 18' by packing rings 24 of felt or other suitable material, and in front of said supporting ring a folded parachute 27 of cloth, plastic or the like is stowed in the space 22. In front of this parachute and behind a second supporting ring 28 attached to the shell 20 cords or lines 29 are wound round the shell 20 said cords or lines connecting the corners of the parachute with the fore or top end of the shell 20. The stowed parachute and the cords occupy substantially the entire annular space 22. Contrary to prior rockets, in which the parachute of cloth or the like with suspension cords is stowed in front or rear of the case or shell 20, the parachute and cords in the rocket device according to the invention do not contribute to any increase of the length of the rocket. Thus a relatively short rocket will be obtained which is favourable from the point of view of stabilization.

When the parachute and the cords are provided in the rocket as herein proposed, the parachute upon launching will be folded up normally.

A further factor supporting the stabilization is a damping device connecting the parachute suspension cords 29 with the useful load or shell 20. Said damping device by preference comprises two springs 30 in the form of plane spirals which are formed of a single wire, such as galvanized soft iron wire, said spirals at the outer periphery running into each other. In the centre of the rear or lower spiral the wire has a rear extension forming a foot 31 which by plastic 32 or other means is fixed to the top end of the shell 20 or the useful load 21. The opposite end portion of the wire extending from the centre of the spiral spring forms an eye or loop 33 to

which the ends of the suspension cords 29 of the parachute 27 are fastened. It is to be understood that in the position in the rocket the spring device 30 will constitute a relatively great weight in the fore end of the rocket.

When the rocket is to be launched, the outer tube 1 is held in the one hand of the operator, and upon removal of the top cap 3 the other hand rotates the bottom cap 2 an angle sufficient to release the striking pin 8 which by the spring 12 is forced against the primer 13. The powder charge 18 is ignited immediately, and the combustion gases remove the primer 13 and the washer 13' breaking through or burning the cover 15 and launching the rocket casing 19 and the parts connected therewith from the outer tube 1. In the movement in this tube the resilient blades 25 will slide over the inner wall of the tube 1, and immediately after leaving said tube the resilient blades 25 will spring out to radial position in which they offer relatively great air resistance. Due to the position of the parachute and the suspension cords the rocket will be relatively short and due to the weight of the damping device 30 the centre of gravity of the rocket will be placed relatively far forward. These features of construction will promote the flight stability of the rocket so that it will substantially maintain its initial direction. In the same degree as the speed of the rocket is increased the resilient blades 25 will be bent by the air resistance so that their free ends will be directed rearwardly. In the last stage of the combustion of the powder charge 18 the combustion will be transmitted through the delayed-action fuse 18' to the illuminating composition 21, and by the combustion gases thus formed the shell 20 with its contents 21 and the parts 27, 29, 30 connected to the shell are launched from the rocket casing 19. While the parachute folds up itself, the shell 20 with the burning illuminating composition 21 is falling. The jerk arising in the cords will cause a considerable stress in said cords if the connection between the cords and the light body were non-resilient. By the arrangement of a spring device 30 said jerk is damped, and due to this fact relatively thin or weak suspension cords can be used. The spring device will also protect the cords and the parachute from being burnt by the burning composition 21. The empty rocket casing 19 with the motor casing 17 and the guide fins 25 will fall down separately.

As an example it may be mentioned that according to the present invention a distress signal rocket with illuminating composition, parachute, suspension cords and damping device has been created complying with the standards prescribed by international convention and having a volume which is only about $\frac{1}{8}$ of a representative type of rocket for the same purpose in the market.

The invention is not limited to the embodiment of the rocket device described with reference to the drawing. The various details of the rocket may have other shapes than shown. The light body 21 may, for example, be replaced by another object or device. The blades 25 may be replaced by a guiding or stabilizing device of another construction. For example, said device may consist of substantially straight steel blades which are parallel with the axis of the rocket the fore and rear ends of which are fastened to rings telescoping over the tubular rocket casing 19. In the discharge of this casing it is initially moved in relation to the unit of said blades and rings so that this unit forms an extension of the rocket casing and the flat sides of the blades in cooperation with the inner wall of the outer tube 1 will guide the rocket casing a distance corresponding to the length of the unit after the rocket casing itself has left the outer tube 1.

What I claim is.

1. A rocket device comprising an outer container, a tubular rocket casing in said container, a motor case containing a propulsion charge positioned in and closing the

lower end of said rocket casing, means within said outer container to ignite said propulsion charge, a shell positioned against and above said motor case within said rocket casing, said shell having an outer diameter which is substantially smaller than the inner diameter of said rocket casing providing an annular space between said shell and said rocket casing, a foldable parachute, suspension cords connecting the parachute to the upper end of said shell, an illuminating composition substantially filling said shell, said annular space containing said parachute and cords in stowed condition, and pyrotechnic means for launching said shell with illuminating composition, parachute and suspension cords from said rocket casing and for igniting said composition at the end of the combustion of said propulsion charge.

2. A rocket device as claimed in claim 1 wherein supporting rings for the packed parachute and cords limit said annular space in the axial direction thereof.

3. A rocket device comprising an outer container, a tubular rocket casing in said container, a cylindrical motor case containing a propulsion charge and positioned in and closing the lower end of said rocket casing, means within said outer container to ignite said propulsion charge, a shell positioned above and in end to end abutment with said motor case within said rocket casing, said shell having an outer diameter which is substantially smaller than the inner diameter of said rocket casing providing an annular space between said shell and said rocket casing, a foldable parachute and suspension cords for same contained in said annular space, an illuminating composition substantially filling said shell, a metal spring on the top end of said shell and at the top of said rocket casing, said spring connecting said suspension cords with said top end of said shell and pyrotechnic means for launching said shell with illuminating composition, parachute, suspension cords and metal spring and for igniting said illuminating composition at the end of the combustion of said propulsion charge.

4. A rocket device as claimed in claim 3 wherein said metal spring consists of at least one spiral of metal wire in stowed condition being plane and resting on a top end wall of said shell.

5. A rocket device as claimed in claim 3 wherein the metal spring consists of two substantially plane spirals formed of a metal wire, said spirals being superimposed on each other and running into each other at the periphery, a wire portion extending from the center of one wire spiral and connected to a top end wall of said shell, a wire portion extending from the center of the second wire spiral, and a means formed by this latter wire portion for connection to said suspension cords.

6. A rocket device comprising an outer tubular container, a tubular rocket casing positioned in said container co-axially therewith, a guide fin device within said container connected to the lower end of said rocket casing, a motor case containing a propulsion charge positioned in and closing the lower end of said casing, means within said outer container for igniting said propulsion charge, a tubular shell positioned in said casing coaxially therewith and abutting said motor case, an illuminating composition substantially filling said shell, a foldable parachute, suspension cords connected to the parachute, an annular space being provided above said motor case between the inner side of said rocket casing and the outer side of said shell, said space having said parachute and suspension cords therein in their stowed condition, a metal spring positioned above said shell joining said cords to said shell, and pyrotechnic means for launching said shell with illuminating composition, parachute and suspension cords from said rocket casing and for igniting said composition at the end of the combustion of said propulsion charge.

7. A rocket device comprising an outer tubular open end container, a tubular rocket casing extending longitudinally within said outer container, a rocket motor case containing a propulsion charge positioned within and closing one end of said tubular rocket casing, resilient fins

connected to said rocket motor case and extending along said outer container, means connected to said outer container for igniting said propulsion charge, a tubular shell positioned in end to end abutment with said motor case and within and extending longitudinally of said tubular rocket casing, but spaced therefrom providing a space therebetween above said motor case, an illuminating composition substantially filling said shell, a parachute with suspension cords surrounding said tubular shell within said space between said shell and said tubular rocket casing, pyrotechnic means for propelling said shell and parachute and illuminating said illuminating composition

positioned between said motor case and one end of said shell, and a metal spring attached to and positioned on another end of said shell and connected to said suspension cords.
